PROCESS OF ALKYLATING AROMATIC HYDROCARBONS

Robert E. Burk, Wilmington, Del., and Everett C. Hughes, Cleveland Heights, Ohio, assignors to The Standard Oil Company, Cleveland, Ohio, a corporation of Ohio

Application December 16, 1944, Serial No. 568,558

14 Claims. (Cl. 260—671)

This invention relates to the alkylation of aromatic hydrocarbons in the presence of hydrogen fluoride as a catalyst in the vapor phase promoted by boron fluoride.

It has been known to alkylate aromatic hydrocarbons with propylene or higher olefins by hydrogen fluoride as catalyst, without a promoter. While operative with these olefins, the hydrogen fluoride is not sufficiently active for ethylene, giving for instance but little more than sixty per cent conversion of ethylene, whereas propylene is reacted completely. We have now found however, that alkylation may be so directed, by suitable process steps and conditions, as to react ethylene particularly successfully, and also to form selectively mono-alkylated products of higher alkylated products as may respectively be desired.

To the accomplishment of the foregoing and related ends, the invention, then, comprises the features hereinafter fully described, and particularly pointed out in the claims, the following description setting forth in detail certain illustrative embodiments of the invention, these being indicative however of but a few of the various ways in which the principle of the invention may be employed.

Olefins which may be used are notably those which are normally gaseous, as ethylene, propylene, butylenes, mixtures of olefins, or olefin-paraffin mixtures. Refinery gases containing both paraffins and olefins may be conveniently used without separation, and an especial advantage of the invention is the ability to operate with dilute olefin-containing gases. The olefins may be reacted with aromatic hydrocarbons such as benzene, toluene, etc. If it is desired to produce particularly mono-alkylated aromatic compounds the ratio of olefin and aromatic hydrocarbon should be in the order of up to 15, and usually 3 to 15, mols of aromatic to each mol of olefin. If the production of higher alkylates is desired, this ratio should be reversed.

A further factor favoring mono-alkyl derivatives is the application of hydrogen fluoride as catalyst in the vapor phase. This catalyst is promoted, in particular by providing a smaller amount of boron fluoride as promoter. The amount of hydrogen fluoride catalyst applied may be from 1 to 40 weight per cent (based on the aromatic), depending upon the extent of action desired, and usually preferably around 5-15 weight per cent. The promoter, boron fluoride, may be supplied in such minor proportions as from $\frac{1}{4}$ to 20 per weight per cent (based on the aromatic).

The operating conditions should include a

temperature at which the reaction proceeds at a satisfactory rate, and a pressure to assure that the hydrogen fluoride and boron fluoride are in the vapor phase at said temperature. The olefin generally is in the vapor phase and the aromatic will be in the liquid or vapor phase, depending on the temperature and pressure conditions. The temperature may be selected, among other things, in relation to the amount of the catalyst employed, the relative proportions of the fluorides, and the speed of the reaction desired. The lower temperature limit is that at which the reaction proceeds at a desired rate and the upper temperature limit is one in which the alkylation of aromatics is still the primary reaction. A temperature for suitable operating conditions can readily be selected in view of this explanation. In a commercial operation which takes into account economic and other operating factors, a temperature within the range of 0° to 375° F. probably will be selected, and within this range a temperature of 90° to 200° F. is preferred. The pressure may be any pressure except that it must not be so high as to cause either of the fluorides to be in the liquid phase at the prevailing temperature. For example, if the reaction temperature is about 67° F. (boiling point of hydrogen fluoride) the pressure in the reaction should not be in excess of atmospheric. At reaction temperatures below the boiling point of hydrogen fluoride, the pressure would be less than atmospheric. However, in order to obtain desirable reaction rates and high yields in a reasonable time, temperatures somewhat above 67° F. are generally employed and it is therefore possible to use super-atmospheric pressure, such as in excess of 50 pounds per square inch, and at much higher temperatures up to 500 pounds per square inch.

The catalyst components all or in part may be brought in with the aromatic hydrocarbon, where preferred. In one desirable mode of operation, the promoter, boron fluoride, is mixed with the olefin and this mixture is then partially saturated with hydrogen fluoride to provide the latter in the desired catalytic amount, and the resulting gas mixture is then passed through an agitated pool of the aromatic hydrocarbon which is to be alkylated.

It is advantageous to recover or absorb the catalyst from the spent gases coming from the reaction zone, and this may be accomplished by contacting them with aromatic feed or with supplementary absorbent or both. And desirably this may be in a counter-current down flow of 55. the feed or absorbent liquid against the rising

gas in tower arrangement, the complete recovery of the catalyst from the off-gas being accomplished and the catalyst being kept in suspension within the reaction tower. Higher alkylated products which are not desired may be recirculated.

As an example: Benzene and an ethylene-containing gas (ethylene content 4.3%) in a mol ratio of 1 to 0.166 of benzene and ethylene respectively, were reacted in the presence of a catalyst comprising vaporous hydrogen fluoride in amount of 10.5 weight per cent (based on the benzene), promoted by 4.1 weight per cent of boron fluoride (based on the benzene), the temperature being 110° F. and the pressure 200 pounds per square inch. All of the ethylene was taken up in the reaction, and of the alkylate product 88.64 per cent was monoethyl benzene, penta and hexa ethyl benzenes were present in only a trace, and the remainder was 10 per cent diethyl benzene and 1.16 per cent of tri and tetra ethyl benzenes.

As a further example: Benzene and a gas containing 5% ethylene were reacted in a mol ratio of 1 to 0.2 of benzene to ethylene respectively in the presence of a catalyst comprising vaporous hydrogen fluoride in an amount of 11.1 weight per cent (based on the benzene) promoted by 5.8 weight per cent of boron trifluoride (based on the benzene) at a temperature of 220° F. and the total pressure of 150 pounds per square inch. Analysis showed that 83% of the ethylene in the gas was taken up in the reaction; the alkylate product contained 86% monoethyl benzene.

As an additional example: A commercial grade of benzene known as "2° benzene," and a gas containing 11.8% propylene and the balance saturates, were reacted at a temperature of 113° F. at a total pressure of 102 pounds per square inch. The reaction was carried on in the presence of a catalyst comprising vaporous hydrogen fluoride in an amount of 21.5 weight per cent (based on the benzene) promoted by a trace of boron trifluoride, i. e., an amount being of the order of $\frac{1}{4}$ to 1 weight per cent or less (based on the benzene). All of the propylene was taken up from the gas during the reaction, and the alkylate formed comprised 75% isopropyl benzene.

Other modes of applying the principle of the invention may be employed, change being made as regards the details described, provided the features stated in any of the following claims, or the equivalent of such, be employed.

We therefore particularly point out and distinctly claim as our invention:

1. In a process of alkylating aromatic compounds, reacting ethylene with benzene in proportions of 1 mol of the former to 3-15 mols of the latter by a large amount of vapor phase hydrogen fluoride promoted by a smaller amount of boron fluoride, at a temperature not over 200° F. and pressure at least 50 pounds per square inch, and feeding in cool benzene to the reaction counter-currently to the off-gas of the reaction to recover at least a part of the fluorides therefrom.

2. In a process of alkylating aromatic compounds, reacting ethylene with benzene in proportions of 1 mol of the former to 3-15 mols of the latter by a large amount of vapor phase hydrogen fluoride promoted by a smaller amount of boron fluoride, at a temperature not over 200° F. and pressure at least 50 pounds per square inch, and feeding a cool absorbent counter-cur-

rently to the off-gas of the reaction to recover at least a part of the fluorides therefrom.

3. In a process of alkylating aromatic compounds, reacting ethylene with benzene in proportions of 1 mol of the former to 3-15 mols of the latter by a large amount of vapor phase hydrogen fluoride promoted by a smaller amount of boron fluoride, at a temperature not over 200° F. and pressure at least 50 pounds per square inch, and feeding a cool liquid counter-currently to the off-gas of the reaction to recover at least a part of the fluorides therefrom.

4. In a process of alkylating aromatic compounds, reacting ethylene with benzene in proportions of 1 mol of the former to 3-15 mols of the latter by vapor phase hydrogen fluoride promoted by a smaller amount of boron fluoride, at a temperature not over 200° F. and pressure at least 50 pounds per square inch.

5. In a process of alkylating aromatic compounds, reacting an olefin which is normally gaseous with a larger proportion of an aromatic hydrocarbon by vapor phase hydrogen fluoride catalyst promoted by a smaller amount of boron fluoride, at a temperature not over 200° F. and pressure at least 50 pounds per square inch, and admixing cool benzene with the off-gas of the reaction to recover at least a part of the fluorides therefrom.

6. In a process of alkylating aromatic compounds, reacting an olefin which is normally gaseous with a larger proportion of an aromatic hydrocarbon by vapor phase hydrogen fluoride catalyst promoted by a smaller amount of boron fluoride, at a temperature not over 200° F. and pressure at least 50 pounds per square inch, and admixing a cool absorbent with the off-gas of the reaction to recover at least a part of the fluorides therefrom.

7. In a process of alkylating aromatic compounds, reacting an olefin which is normally gaseous with a larger proportion of an aromatic hydrocarbon by vapor phase hydrogen fluoride catalyst promoted by a smaller amount of boron fluoride, at a temperature not over 200° F. and pressure at least 50 pounds per square inch, and admixing a cool liquid with the off-gas of the reaction to recover at least a part of the fluorides therefrom.

8. In a process of alkylating aromatic compounds, reacting an olefin-containing gas with a larger proportion of an aromatic hydrocarbon by vapor phase hydrogen fluoride catalyst promoted by boron fluoride, at a temperature not over 200° F. and pressure at least 50 pounds per square inch.

9. In a process of alkylating aromatic compounds, reacting an olefin-containing gas with a smaller proportion of an aromatic hydrocarbon by vapor phase hydrogen fluoride catalyst promoted by boron fluoride, and admixing cool aromatic hydrocarbon with the off-gas of the reaction to recover at least a part of the fluorides therefrom.

10. In a process of alkylating aromatic compounds, reacting an olefin-containing gas with a smaller proportion of an aromatic hydrocarbon by vapor phase hydrogen fluoride catalyst promoted by boron fluoride, and finally admixing a cool absorbent with the off-gas of the reaction to recover at least a part of the fluorides therefrom.

11. In a process of alkylating aromatic compounds, reacting an olefin-containing gas with a smaller proportion of an aromatic hydrocar-

bon by vapor phase hydrogen fluoride catalyst promoted by boron fluoride, and finally admixing a cool liquid with the off-gas of the reaction to recover at least a part of the fluorides therefrom.

12. In a process of alkylating aromatic compounds, reacting an olefin-containing gas with an aromatic hydrocarbon by vapor phase hydrogen fluoride catalyst promoted by boron fluoride at a temperature of not over 200° F. and at a pressure of at least 50 pounds per square inch.

13. In a process of alkylating aromatic compounds, reacting an olefin-containing gas with an aromatic hydrocarbon by vapor phase hydrogen fluoride catalyst promoted by boron fluo- 15

ride at a temperature of not over 200° F. and at a pressure to maintain the hydrogen fluoride and the boron trifluoride in the gaseous phase at said temperature.

5 14. In a process of alkylating aromatic compounds, reacting an olefin-containing gas with an aromatic hydrocarbon by vapor phase hydrogen fluoride catalyst promoted by boron fluoride at a temperature at which the reaction proceeds and at a pressure to maintain the hydrogen fluoride and boron trifluoride in the vapor phase at said temperature.
